FOLDING HORSE

Harry C. Campbell, Toledo, Ohio

Application December 15, 1945, Serial No. 635,168

2 Claims. (Cl. 304—5)

1

My invention relates to folding horses, or trestles, of the type disclosed in my U. S. Letters Patent No. 2,312,956, dated March 2, 1943, and over which the instant invention is designed as an improvement.

My instant invention is designed with the primary object in view of providing an all-metal horse, or trestle, for use in the building trades and comprising parts all of which may be inexpensively stamped out of metal by a punch press or the like.

Another object is to provide in such horses improved means for maintaining the legs of the horse unfolded and rigid, together with means adapting such horses for greater utility than present-day horses, or trestles.

Still another object is to simplify the connection between the legs and the back member and to generally strengthen the composite structure, particularly when unfolded.

Other and subordinate objects, also comprehended by my invention, together with the precise nature of my improvements and the manifold advantages thereof will be readily understood when the succeeding description and claims are read with reference to the drawings accompanying and forming part of this specification.

In said drawings:

Figure 1 is a view in side elevation of my improved horse, or trestle, unfolded.

Figure 2 is a view of the same in end elevation.

Figure 3 is a fragmentary view in perspective, drawn to an enlarged scale.

Figure 4 is a fragmentary view in side elevation, drawn to an enlarged scale, and illustrating in dotted lines the manner in which the legs of one pair are folded.

Figure 5 is a view in vertical transverse section taken on the line 5—5 of Figure 4.

Figure 6 is a fragmentary view in longitudinal section taken on the line 6—6 of Figure 5 and illustrating one of the legs partly folded.

Figure 7 is a view in bottom plan of one of the hinge braces.

Figure 8 is a fragmentary view in longitudinal section of the shelf drawn to a further enlarged scale.

Figure 9 is a fragmentary view in rear elevation of one of the legs.

Figure 10 is a fragmentary view in bottom plan of the back member, and

Figure 11 is a view in bottom plan of one of the hinge plates.

Reference being had to the drawings by numer-

2

als, my improved horse, in the preferred embodiment illustrated, comprises, as usual, an elongated back member 1 and a pair of opposed legs 2 at each end of said member diverging, in each pair, toward the lower ends thereof. The back member 1 and the legs 2 are tubular and preferably of rectangular shape in cross section. A pair of opposed, beveled notches 3 are provided in the sides of the back member 1 adjacent to opposite ends of said member and in which the upper ends of the pairs of legs 2 are adapted to seat when the horse is unfolded, and as shown, for instance, in Figure 3. The back member 1 and the legs 2 may be formed of any light, strong metal suitable for stamping and bending.

Flat feet 4, preferably rectangular, are provided for the lower ends of the legs 2 with shanks 5 fitting in said ends. The feet 4 are also preferably formed of metal.

20 A compound hinge connection is provided between each pair of legs 2 and the back member 1 comprising the following: A transverse row of hinge barrels 6 is formed on the bottom of said member 1 adjacent to each end of the same, with 25 said barrels laterally spaced in the row. The hinge barrels 6 are preferably formed by stamping tongues out of the bottom of said member 1, as best shown in Figure 6, and rolling said tongues into barrel form. The rows of hinge barrels 6 are aligned with the inner edges of the notches 3. A similar row of hinge barrels 7 is 30 similarly provided on the rear side of each leg 2 adjacent to the upper ends of the legs. A rectangular hinge plate 8 with laterally spaced hinge barrels 9, 10, 11 on three edges thereof is provided 35 for each pair of legs 2, with the hinge barrels 9 on one edge of plate 8 alternating with and connecting to the row of hinge barrels 6 by a pintle 12, and the hinge barrels 10, 11 on the other edges 40 of said plate 8 similarly connected, by pintles 13, 14 to the hinge barrels 7 of the legs 2, respectively.

45 As will now be seen, by virtue of the described compound hinge connection, the legs 2 of each pair may be swung toward each other, from unfolded position, on the hinge plates 8 from diverging relation in each pair into substantially parallel relation, and then swung, together with said plates 8, in pairs, alongside the back member 1 substantially parallel with said back.

50 A hinge brace 15 connects the legs 2 of each pair of legs intermediate the ends of said legs, and functions to maintain the legs of each pair in divergent relation. Each hinge brace 15 comprises a pair of links 16, 17 of inverted channel

form with inner ends pivotally connected together, as at 18, and the inner end of one link 16 arranged to overlap the other link 17 to form an upwardly breaking joint between said links whereby the links are prevented from breaking downwardly out of aligned relation. The outer ends of the links 16, 17 are pivoted to the rear sides of the legs 2, as at 19, in brackets 20 and so that said links 16, 17 may be swung upwardly in the plane of the pair of legs 2 connected by the described hinge brace.

Pairs of brace rods 21 are provided for cooperation with the hinge braces 16 to maintain the pairs of legs 2 fully unfolded and said pairs of legs 2 in planes at substantially a right angle to the back member 1. The pairs of brace rods 21 are pivoted, as at 22, to opposite ends of an attaching bracket 23 suitably secured to the bottom of the back member 1 centrally of said member. Hooked outer ends 24 are provided on the brace rods 21 for insertion in slots 25 in the links 16, 17 of the hinge braces 16. As best shown in Figure 3, the slots 24 are spaced apart, and the pivots 22 connect the inner ends of the pairs of brace rods 21 together so that said rods in each pair diverge, relatively, to stabilize the pairs of legs 2 against lateral twisting.

A shelf 26 is provided in the horse structure to extend endwise between the pairs of legs 2. Preferably the shelf 26 is formed of corrugated metal, for strengthening purposes, with the corrugations extending longitudinally of the shelf, and said shelf is formed with hook-shaped upstanding end flanges 27 for reinforcing the ends of the shelf lengthwise. A pair of S-shaped hooks 28 are provided at each end of the shelf 26 upon opposite sides of the longitudinal center of the shelf, said hooks having inner ends 29 riveted, as at 30, to the flanges 27 inside said flanges. The outer ends of the hooks 28 are fitted downwardly in staple-like keepers 31, one of which is provided on the inner sides of each link 16, 17.

It is to be particularly noted that the brace bars 21, and the shelf 26, since the pairs of brace bars 21 incline downwardly from the back member 1 to the hinge braces 16, and the shelf 26 is interposed between said braces, function to maintain the pairs of legs 2 in fully unfolded position and also function to prevent the hinge braces from breaking upwardly, thereby maintaining the legs of each pair in properly divergent relation. Thus, a dual safety provision results by virtue of use of said bars 21 and the shelf 26 so that accidental collapse of the horse cannot occur. If the shelf 26 is detached, when it is not desired to use the same, the brace bars 21 alone will suffice to prevent collapse of the horse, as will be clear. If the brace bars 21 are detached from the links 16, 17, as through accident, the shelf 26 will suffice to prevent the horse from collapsing.

The manner in which the described horse is adapted to be folded and unfolded will be read-

ily understood. By lifting the hooks 28 out of the keepers 31, the shelf 26 may be detached from the hinge braces 16, and by swinging the brace bars 21 upwardly, the hook ends 24 may be disengaged from the slots 25. The hinge braces may then be swung upwardly in between the legs 2 of the pairs and said legs swung on the described compound hinge connection into parallel relation in each pair, and then swung in pairs on said compound hinge connection parallel to the back member 1 with the brace rods 21 lying between the hinge braces 16 and the plates 8 of the pairs of legs. To unfold the horse, the operations described in connection with folding are reversed, as will be clear.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A trestle of the class described comprising a bar-like back member, pairs of legs at opposite ends of said member, compound hinge connections between said member and each pair of legs adapting the legs in each pair to be swung toward each other and each pair of legs to be swung toward said member, pairs of hinge braces between the legs of each pair for preventing swinging of the legs toward each other and comprising break joint connections whereby said braces are operative to swing said legs toward each other, means extending between said member and said braces for locking said braces against break joint operation, and means interposed between the braces of each pair of legs for preventing swinging of the legs toward said member, the first-mentioned means comprising rods pivoted on said member and attached to said braces for detachment therefrom by pivotal movement of the rods.

2. A trestle of the class described comprising a bar-like back member, pairs of legs at opposite ends of said member, compound hinge connections between said member and each pair of legs adapting the legs in each pair to be swung toward each other and each pair of legs to be swung toward said member, pairs of hinge braces between the legs of each pair for preventing swinging of the legs toward each other and comprising break joint connections whereby said braces are operative to swing said legs toward each other, means extending between said member and said braces for locking said braces against break joint operation, and means interposed between the braces of each pair of legs for preventing swinging of the legs toward said member, the second-mentioned means comprising a shelf detachably attached to said braces.

HARRY C. CAMPBELL.
